UNITED STATES PATENT OFFICE

95,811

DESIGN FOR A BOOK END

**Fred D. Farr, Mamaroneck, N. Y., assignor to
Revere Copper and Brass Incorporated, Rome,
N. Y., a corporation of Maryland**

Application January 11, 1935, Serial No. 54,815

Term of patent 14 years

To all whom it may concern:

Be it known that I, Fred D. Farr, a citizen of the United States and a resident of Mamaroneck, county of Westchester, State of New York, have invented a new, original, and ornamental Design for Book Ends, of which the following is a specification, reference being had to the accompanying drawing, forming part thereof.

In the drawing:—

Fig. 1 is a perspective view of the book end, showing my new design in closed position;

Fig. 2 is a perspective view of the book end in extended position;

Fig. 3 is an end elevational view of the book end shown in Fig. 1; and

Fig. 4 is a side elevational view of the book end shown in Fig. 1.

I claim:—

The ornamental design for a book end, substantially as shown and described.

FRED D. FARR.
